[57] CLAIM

The ornamental design for a retainer clamp for elongated bodies or the like, as shown and described.

DESCRIPTION

FIG. 1 is a top plan view of a retainer clamp for elongated bodies or the like showing my new design; FIGS. 2 and 3 are respectively front and rear elevational views thereof;

FIG. 4 is a left side elevational view thereof;

FIG. 5 is a cross-sectional view thereof taken along line V—V in FIG. 2;

FIG. 6 is a cross-sectional view taken along line VI—VI in FIG. 4;

FIG. 7 is a front, top and right side perspective view thereof;

FIG. 8 is a front, top and right side perspective view of one unit portion of the retainer clamp, with a second unit portion rotated 90° from its position in FIG. 7; and FIG. 9 is a front, top and right side perspective view of one portion of the retainer clamp shown independently and separately for clarity of illustration.
